ABSTRACT: A circuit arrangement for the production of current impulses with very steep flanks, utilizing current impulses of an impressed current source, in which the current impulse source is connected to a voltage supply therefor with a time dependent voltage source, with the impulse current source being supplied at its load, during the initiation of an impulse, with the full operating voltage and thereafter for the remainder of the impulse with an operating voltage which covers only the circuit losses.

CIRCUIT ARRANGEMENT FOR PRODUCING CURRENT IMPULSES WITH VERY STEEP FLANKS

The invention relates to a circuit arrangement for producing current impulses with very steep flanks, utilizing current impulses of an impressed current source.

Such circuit arrangements are especially needed in rapid storers with magnetic cores which require high pulse currents with very steep flanks. Newly developed rapid storers with magnetic cores are characterized by very short signal paths and therewith by high packing densities of the switching devices. Due to heating these high packing densities require circuits with extremely low loss. Since in storers with magnetic cores the greatest part of the power loss is converted in the control switching network, a reduction of the minimum losses therein is necessary.

The control switching networks used to date operate either on the principle of constant current or constant voltage. In both cases, however, the networks are supplied with a constant operating voltage which results from the necessary rise time and the inductivity or, as the case may be, the characteristic impedance of the circuit to be fed.

In the drawings, wherein like reference characters indicate like or corresponding parts:

FIG. 1 is a diagram of a circuit employing constant current feed;

FIG. 2 is a block diagram illustrating the basic concept of the invention;

FIG. 3 is a circuit diagram illustrating one embodiment of the invention; and

FIGS. 4 and 5 are circuit diagrams illustrating further embodiments of the invention.

In the example of the constant current feed of a circuit illustrated in FIG. 1, there is provided a source of current impulses comprising a transistor T_1 and a resistance R_1 which is connected to a source of constant current and has a circuit L as a load which is short-circuited at the one end and terminated at the input end by its characteristic impedance Z . The voltage appearing at the input of the circuit, following the connection of the transistor, breaks down after the double travel time and stands at the transistor T_1 for the remaining duration of the impulse. In this way an unnecessarily great power loss is converted in the transistor.

The problem underlying the invention is to produce circuit arrangements for the production of current pulses, for example, as used for the control of core storers, with retention of the desired flank steepness of the control impulse and achievement of a low power loss. This problem is solved in accordance with the invention by connecting the current impulse source to a voltage supply with a time dependently controlled voltage source, the current impulse source preferably being supplied with a full operating voltage only during the duration of initiation of an impulse in its load and is thereafter supplied for the residual duration of such impulse with an operating voltage covering merely the switching network losses.

As indicated in FIG. 2, the load circuit V is fed from a current source Q_1 which in turn is supplied from a voltage source Q_U with an operating voltage adjusted to the requirements and which is dependent upon time. The high operating voltage U (see FIG. 1), which is required only for the duration of the initiation of an impulse, is switched over in the steady state condition to a considerably smaller operating voltage. The average power loss is thereby considerably reduced, at the same time retaining the desired steepness of the impulse flanks.

In the embodiment of FIG. 3 the voltage at the feed point P ,

following connection of the current impulse source Q_1 is derived for the short duration of the initiation of an impulse from condenser C , which was previously charged through a resistance R_2 to a high voltage U_2 . In the normal steady state condition, on the other hand, the current impulse source Q_1 is supplied, through the diode D_1 , with the considerably lower voltage U_1 .

In cases in which the circuit is operated with a very small keying ratio, it is practical to replace the resistance R_2 by a switch S , as indicated in FIG. 3 by the broken lines.

FIG. 4 illustrates an embodiment in which the voltage necessary for the operation of the current impulse source Q_1 , for the duration of the initiation of an impulse, is derived through a switch S from the voltage source U_2 . In the steady state condition the switch S is switched off and the current impulse source Q_1 is operated from the low voltage source U_1 which is sufficient to cover the losses. The switch S can feed directly into the point P or can be coupled by a transformer $\bar{U}$ or by a condenser.

20 In the embodiment illustrated in FIG. 5 the switch S is temporarily connected prior to the operative connection of the current impulse source Q_1 . A transformer $\bar{U}$ transforms the low voltage U_1 to a high value and charges the condenser C therewith. When the charging procedure is terminated, the current impulse source Q_1 is switched in, which is fed for the duration of the impulse initiation from the condenser C as well as through the transformer $\bar{U}$, provided that the switch S , as illustrated in the circuit arrangement in FIG. 4, is not temporarily switched off until after the initiation of an impulse. 25 This arrangement has the additional advantage that only a single voltage source is required, namely the low voltage U_1 .

The circuits indicated in FIGS. 3 to 5 are common to the transistor T_1 and the resistance R_1 , and comprise primarily the current impulse source Q_U , whose output current i is approximately proportional to the input voltage on the base of the transistor, provided that the voltage at the point P applied by the voltage source Q_U is sufficiently large. The applied voltage at the point P has a high value only for the short duration of the initiation of an impulse. For the remaining part of the impulse duration the current impulse source Q_1 will be operated with the lower voltage U_1 . Consequently the transformed power loss in the circuits will be kept very low. The lower limit of the voltage U_1 is determined merely by the voltage drops in the semiconductors, across the resistance R_1 , and the loss of the line or circuit L .

Changes may be made within the scope and spirit of the appended claims which define what is believed to be new and desired to have protected by Letters Patent.

I claim:

- 50 1. A circuit arrangement for the production of current impulses with very steep flanks, comprising a first switch, a load operatively connected to said first switch, and a voltage supply connected to said first switch and including means for developing a first voltage during the initiation of a current impulse at said load, means for developing a second voltage having a value less than said first voltage during the remaining duration of the current impulse, a voltage source, said second voltage developing means including a first diode connected between said voltage source and said first switch, said first voltage developing means including a capacitor connected in parallel with said first diode, a second diode, a transformer having a secondary winding connected in series circuit with said second diode, said series circuit being connected in parallel with said capacitor, and a second switch, said transformer having a primary winding connected between said voltage source and said second switch.
